KNITTING MACHINE NEEDLE

Arthur Currier, Penacook, N. H., assignor to
Acme Knitting Machine & Needle Company,
Franklin, N. H., a corporation of New
Hampshire

Application June 13, 1931. Serial No. 544,064

5 Claims. (CL 66—122)

This invention relates to knitting machine needles of the latch type and to methods of making such needles.

In making needles of this character according to the usual commercial processes, the needle shaft or body is slotted to take the latch, the walls or cheeks of the slot are drilled to receive the latch pivot, and the latch and shaft then are assembled with the shank of the latch located in the slot in the needle shaft and the hole in the latch lined up approximately with the holes drilled in the walls of the slot. Usually the outer ends of both holes are counter sunk, and it is the common practice to punch these counter sinks prior to drilling the holes. A pivot pin or wire next is driven through the aligned holes, and it is cut off or trimmed, if necessary, after which the ends of the pin are headed to secure the pivot firmly in place. This heading operation causes some incidental upsetting of the central part of the pivot, and because of this fact it is the usual practice to make the hole in the latch somewhat larger than the holes in the cheeks or walls of the latch slot.

25 The wire from which the pivots are made may be either plain or screw threaded. If a threaded wire is used, then the holes drilled in the needle cheeks must be tapped prior to inserting the pivot.

30 In using these needles it occasionally happens that the pivot of a needle latch will work loose sufficiently to allow the pivot to move endwise out of place. This occurs with both types of pivot constructions just described. When it happens the pivot will sooner or later catch and hold a loop of thread, thus producing a flaw in the work which makes the stocking, or other article being knit, unsalable. Accidents of this kind are particularly disastrous when knitting silk hosiery or other fine goods. While the percentage of needles which become defective in this manner is relatively small, it is, nevertheless, sufficient to be an item of considerable importance to manufacturers of hosiery and other knit goods.

45 The present invention deals especially with these considerations. It aims to improve both the construction and methods of manufacture of knitting machine needles with a view to substantially eliminating, or at least greatly reducing, the liability of the latch pivots working loose. To this end it involves both a novel pivot construction and also a novel process of securing a latch pivot in a needle shaft.

50 The nature of the invention will be readily understood from the following description when

read in connection with the accompanying drawing, and the novel features will be particularly pointed out in the appended claims.

In the drawing,

Figure 1 is a side elevation of a knitting machine needle of the general type with which the invention is concerned;

Figs. 2, 3, 4 and 5 are side elevations on a large scale of the hook and latch portions of needles constructed in accordance with this invention;

Fig. 6 is a sectional view on a large scale through the parts of a needle adjacent to the pivot and illustrating a step in the method provided by this invention;

Fig. 7 is a view similar to Fig. 6 after the operations on the pivot have been completed; and

Fig. 8 is a view similar to Fig. 7 illustrating a modification.

According to the method provided by this invention the needle shaft or body 2 and the latch 3 may be made in any suitable or convenient manner. In a typical process the hook 4 is made and bent into its final shape, and the slot 5 for the latch 3 is formed at any convenient point in the process. The hole 6, Fig. 6, for the latch pivot is drilled and is counter sunk, as shown at 7. Usually, as above indicated, the counter sink is first punched and a hole is drilled afterwards. According to the preferred practice the hole for the pivot, instead of being drilled through both walls or cheeks 8 and 9 of the slot 5 is formed through one wall only, and the point of the drill is allowed to enter the opposite wall to form a recess 10, Fig. 6.

The latch 3 and needle shaft 2 are next assembled with the hole *h* in the latch properly registered with the hole 6, and a pivot wire or pin 12 then is inserted through both holes. For this purpose the end of a length of wire may be inserted in the holes and then cut off, the inner end of the wire being located in the socket 10.

It will be observed that the hole 6 is considerably smaller in diameter than the hole *h* in the latch.

The pivot 12 is next upset to substantially fill the hole *h*. This operation preferably is performed by subjecting the pin to the action of two opposed hammers or headers 13 and 14, Fig. 6, the former acting directly on the exposed end of the pivot 12 and the latter in line with the former, but engaging the cheek or wall 9. Both hammers or headers are vibrated rapidly, and the result of their action is to upset the metal of the pivot so as to make a head *a*, Fig. 7, located in the counter sink 7, to form an upset enlarge-

ment *b* which substantially fills the hole in the latch 3, and to shape the inner end *c* of the pivot to fit the recess 10. While this involves a very substantial distortion of the pin, this result is 5 readily accomplished when the pin is made of suitable metal, such as those commonly used heretofore for latch pivots.

It will be observed that the pivot stud, when finished, conforms substantially to the dimensions of the parts in which it is located. It consists of the head *a*, the enlargement *b* on which the latch 3 swings, the extension or point *c*, and a reduced neck portion *d* which connects the parts *a* and *b*. In this construction, therefore, 10 the finished pivot stud 12' is headed or riveted to one wall, namely, the wall 8 of the slot 5, but it is secured to this wall only. It is centered in the other wall due to the presence of the extremity *c* located in the recess 10, but it is not secured to 15 the opposite wall 9.

It has been found desirable to perform the heading operation in the manner above described by blows directed axially in line with both ends of the pivot since this forms a more symmetrical 20 enlargement *b*, filling the hole in the latch 3 more completely, and producing definite and well formed shoulders on both ends of the enlargement *b*. In other words, end faces are provided 25 on this enlargement which bear against the opposite walls of the slot 5, the upper of these faces, as shown in Fig. 7, cooperating with the head *a* to 30 secure the stud rigidly to the wall 8. While the inner end of the pin does not, of course, come in contact with the hammer or header 14, nevertheless the action of this header seems to aid 35 materially in promoting a better flow of the metal of the stud adjacent to the wall 9, facilitating the upsetting of the stud against this wall, and producing a better shaped and stronger pivot 40 stud.

The reasons for the superiority of this construction over those heretofore used are somewhat obscure, although they have definitely been established in practice. It seems to be due, at 45 least in some measure, to the fact that a superior union of the pivot stud to the wall 8 in which it is secured is produced. Apparently, also, the fact that the pivot is secured in one wall only is an 50 advantage, at least in needles of the smaller sizes, and these are, of course, the needles in which the greatest amount of trouble is experienced due to the pivots working loose. It seems probable 55 that when one of these needles is in operation in a knitting machine it is subjected to forces which tend to produce a relative vibration or other movement of the two walls of the slot toward 60 and from each other. The thickness of metal is very small, and imperfections in securing the pivots may be such that they cannot be detected 65 by inspection and yet will permit such relative movement or vibration to start while the needle is in use. When once started the wear so occasioned will tend to increase the difficulty very rapidly. The circumstances will be more readily 70 understood from a consideration of the fact that in a forty-eight gage needle, for example, the thickness of the walls 8 and 9 is only about eight thousandths of an inch. The shank of the latch 3 is of approximately the same thickness. The wire of the pin 12 is only thirteen thousandths of an inch in diameter in a typical needle of this size. The parts, therefore, are very small and any imperfections, particularly in the heading operation, are of correspondingly greater importance 75 than they would be in needles of considerably

larger sizes. When a forty-eight gage needle is made according to the method above described the pivot hole in the latch 3 is made approximately eighteen thousandths of an inch in diameter, and the rivet is upset until it approximately fits this hole, sufficient clearance only being provided to let the latch swing freely. This clearance may be produced after the heading operation and during the tumbling of the needles. The dimensions of the head *a* and enlargement *b*, however, are such as to provide a very secure anchorage 80 for the pivot stud. Any tendency of the walls 8 or 9 to vibrate or to spread apart does not affect this anchorage, so that the pivot stud remains 85 permanently secured to the wall 8 until it has been practically worn off. Wear tests made on these needles have demonstrated that this is 90 the case.

The foregoing construction also overcomes many of the disadvantages of the screw threaded pivot type of needle which is the most common type of latch needle in use today. These screw threaded pivots also are headed but this operation must be performed very carefully in order 95 to avoid stripping the threads, and consequently 100 only a very limited heading or expanding of the pivot can be produced. In such a needle also the latch must ride on the threads of the pivot so that the initial wear on the pivot is rapid due to the fact that a very small area only of metal 105 is in contact with the latch. These objections are overcome in the present construction. In addition the needle construction provided by this invention eliminates the necessity for tapping 110 the holes, with the incidental liability of springing the cheeks or walls of the slot so that they 115 will not line up properly.

While a typical construction of the rivet is shown in Fig. 7, it will be evident that essentially 115 the same results could be secured notwithstanding minor variations in the shapes of the parts. For example, the head *a* could be given other forms such as those shown at 13, 14 and 15 in Figs. 2, 3 and 4. The recess 10 in the wall of 120 the slot opposite to that in which the rivet is anchored also could be differently shaped, or might even be omitted as shown in Fig. 8, although I prefer to have the inner end of the pivot 125 stud centered in this wall. These and various other changes could be made within the spirit 125 and scope of the invention.

After the heading operation has been completed the needle may then go through the usual hardening and finishing operations, no change 130 in these steps of the usual manufacturing process being required by the present invention.

Having thus described my invention, what I desire to claim as new is:

1. A knitting machine needle provided with a slot, a latch having a shank located in said slot, and a pivot stud extending through one wall only of said slot and supporting said latch for swinging movement, said stud having an enlarged end portion bearing against the opposite wall of said slot and substantially filling the hole 140 in said latch.

2. A knitting machine needle provided with a slot, a latch having a shank located in said slot, and a pivot stud supporting said latch for swinging movement and secured in one wall only of 145 said slot; said stud comprising an enlarged portion substantially filling the hole in said latch, a head bearing against the outer surface of said wall, and a reduced neck connecting said head with said enlarged portion.

3. A knitting machine needle as defined in preceding claim 2 characterized by the fact that said stud also includes an end portion located in a shallow recess formed in the opposite wall of said slot. 80
4. A knitting machine needle according to preceding claim 2 characterized by the fact that said stud also includes a pointed extension projecting from said enlarged portion and located in a shallow recess formed in the opposite wall of said slot. 85
5. A knitting machine needle provided with
